(57) **CLAIM**

The ornamental design for a roulette carpet, as shown and described.

DESCRIPTION

The file of this patent contains at least one drawing executed in color. Copies of this patent with color drawings will be provided by the Office upon request and payment of the necessary fee.

The single drawing contains an illustration showing a carpet including my new roulette design. The single view of the design represents the top surface of the carpet, with no other portions of the carpet forming part of the claimed design.
